UNITED STATES PATENT OFFICE

118,972

DESIGN FOR A COMBINED NIGHTGOWN AND CRIB COVER

Bertha Braun Friedman, New York, N. Y.

Application December 28, 1939, Serial No. 89,163

Term of patent 7 years

To all whom it may concern:

Be it known that I, Bertha Braun Friedman, a citizen of the United States of America, residing in New York city, in the Borough of Manhattan, county and State of New York, have invented a new, original, and ornamental Design for a Combined Nightgown and Crib Cover, of which the following is a specification, reference being had to the accompanying drawings, forming part thereof, wherein,

I claim:

The ornamental design for a combined nightgown and crib cover, substantially as shown.

BERTHA BRAUN FRIEDMAN.
